Inventor

UNITED STATES PATENT OFFICE.

OTTO HOLGERSON, OF PEABODY, KANSAS.

COLLAPSIBLE CHAIR.

1,127,247.

Specification of Letters Patent.

Patented Feb. 2, 1915.

Application filed December 8, 1913. Serial No. 805,301.

To all whom it may concern:

Be it known that I, OTTO HOLGERSON, a citizen of Denmark, (who has taken out his first naturalization papers for citizenship in the United States of America and intends to take out his final papers as soon as he can,) now residing at Peabody, in the county of Marion and State of Kansas, have invented certain new and useful Improvements in Collapsible Chairs, of which the following is a specification.

This invention relates to improvements in collapsible stools or chairs, the object in view being to provide a structure susceptible of being folded into very compact form for carrying the same or for disposition when not in use.

A device constructed in accordance with my invention comprehends a supporting standard to which are connected at one end legs capable of being folded about said standard in spaced relation to each other and at its other end seat supporting arms adapted for folding similarly about the standard into the spaces between the legs aforesaid.

In carrying out the invention it is contemplated to employ an envelop or bag into which the folded chair may be closed to facilitate carrying of the same, which envelop is adapted to coöperate with the chair when it is unfolded into operative position to form a back rest therefor.

With the above and other objects in view, this invention consists in the construction, combination and arrangement of parts all as hereinafter more fully described, claimed and illustrated in the accompanying drawings, wherein:

40 Figure 1 is a side elevation of a chair constructed in accordance with my invention in extended operative position. Fig. 2 is a rear elevation of the same. Fig. 3 is a view of the chair in collapsed position and showing in dotted lines the position assumed by seat arms in their collapsing movement. Fig. 4 is a fragmentary plan view of the seat member. Fig. 5 is an enlarged detail view of one of the bracket members carried by the chair standard to which the leg and arm elements are connected. Fig. 6 is a fragmentary view of the chair standard, partly in section and showing more clearly the locking member for holding the legs in extended position.

Specifically describing a chair or stool

constructed in accordance with my invention, the numeral 1 represents a vertical standard or post comprising spaced members and to the lower extremity of the same 60 is fixedly secured a bracket 2 shown more clearly in Fig. 5 of the drawings. The bracket 2 is formed with a plurality of arms bifurcated at their outer extremities, three of such arms being employed in the actual 65 construction of my device. Pivottally secured in the bifurcated portions of the arms of the bracket 2 are supporting legs 3, to intermediate points of which are connected one end of coöperating brace members 4, 70 the other end of each brace member being similarly connected to a slidable bracket 5 similar in construction to the bracket 2 hereinbefore mentioned. In the position shown in Figs. 1 and 2 of the drawings, the 75 legs 3 are held in their extended or operative position by means of the brace members 4 and the bracket member 5 which is mounted for sliding movement vertically between the side members of the standard 1. Locking means engaging the bracket member 5 80 so as to prevent movement of the same and collapsing of the legs 3 is employed and consists of a spring member 6 secured to the standard 1 at one end and having an inwardly projecting extension 7 adjacent its other end and adapted to pass through one side of the standard 1 over the bracket 5. A finger-piece 8 is formed on the spring member to facilitate disengagement of the 85 locking means when it is desired to collapse the legs.

It will be noted that the upper end of the standard 1 has fixedly secured thereto a third bracket 2' similar in construction 95 to the brackets 2 and 5 and said bracket 2' has pivotally connected thereto the seat supporting elements. These elements comprise the rearwardly extending divergent pair of arms 9 and a third arm 10 projecting forwardly of the chair. The seat member 11 shown most clearly in Fig. 4 is of triangular shape and carries at its rear corners hook members 12 adapted to engage about the headed projections 13 mounted 100 in the free extremities of the rear arms 9. The seat has also at its forward corner a hook or eye 14 adapted to engage over the free extremity of the seat supporting arm 10 which extremity is notched to insure 105 positive engagement of the eye therewith. It will be obvious that the triangular forma-

tion of the seat and particular arrangement of the arms permits said arms to be held in extended operative position by the seat member 11 and upward movement of the 5 arm 10 is limited by the provision of a rearwardly extending arm 15 connected to the arm 10 intermediate of the same and adapted for abutment against the short projection 16 secured to the upper extremity 10 of the standard 1. Not only does the arm 15 and its coöperating member 16 limit upward movement of the arm 10 but it also prevents collapsing or further upward movement of the seat supporting arms when 15 pressure is applied to the seat member 11 as when a person sits thereupon.

Pivotedly secured to each of the diverging seat members 9 at their outer extremities and mounted on the pivot members 13 20 is a back standard 17 adapted to be moved into a vertical position such as shown in Figs. 1 and 2 when the chair is in use and the lower extremity of each of these standards is bent laterally as indicated at 25 17' so as to coöperate with the under edge of its contiguous seat member 9 to limit the pivotal movement of the standard. The standards 17 aforesaid are adapted 30 to perform the function of a back rest and the envelop or back 18 in which the folded chair is adapted to be carried, is disposed over the standards with the latter projecting into the pocket of the envelop as 35 shown most clearly in Fig. 2 of the drawings. The back rest is, therefore, formed by coöperation of the bag with the upright members 17 and as hereinbefore stated contains a pocket portion which is closed by the flap 19 having suitable fastening members 20 thereon and preferably a strap member 21 is secured to the bag to facilitate carrying of the chair when folded and inclosed therein.

From the foregoing description, it will be 45 understood to collapse the chair comprehended by this invention, the locking mem-

ber 6 is withdrawn from engagement with the bracket 5 and grasping one or more of the legs 3 they are forced upwardly about their pivots moving the bracket member 5 50 in its guiding slot or between the spaced side members of the standard into the full folded position shown in Fig. 3. The seat member 11 is then disengaged from the supporting arms 9 and 10 which are depressed 55 into a position adjacent the standard and lying intermediate the upfolded legs 3. The back rests 17 from which have been previously removed the bag 18 are simultaneously moved on their pivots as shown in dotted 60 lines in Fig. 3 so as to lie parallel with their coöperating seat supporting arm 9. The folded chair is then inserted in the bag 18 along with the flexible seat member 11 and it will be apparent that a very small compact article is provided by this peculiar arrangement of parts.

As shown in Fig. 4 the seat member 11 may comprise a flexible fabric reinforced by leather cross straps 11' so as to prevent 70 distortion or stretching of the material.

Having thus described the invention, what I claim as new is:

In a collapsible chair, the combination of a standard, a bracket fixed to the upper 75 portion of the standard, arms pivoted thereto and adapted to be engaged by a flexible seat member, a plate fixed to the upper portion of the standard and extending on an incline therefrom, the said plate having an 80 offset portion, and an arm pivoted to one of the seat engaging arms and having a free end adapted to engage the offset portion of said plate for retaining the arm against inward collapse.

In testimony whereof I affix my signature in presence of two witnesses.

OTTO HOLGERSON.
